[57] CLAIM

The ornamental design for an electrical connector housing, as shown and described.

DESCRIPTION

FIG. 1 is a top plan view of an electrical connector housing showing our new design;

FIG. 2 is a front elevational view thereof;

FIG. 3 is a bottom plan view thereof;

FIG. 4 is a rear elevational view thereof;

FIG. 5 is a right side elevational view thereof;

FIG. 6 is a left side elevational view thereof;

FIG. 7 is a central cross sectional view of FIG. 2. The view looking left is the same as the view looking right.

FIG. 8 is a perspective view thereof showing our new design on a reduced scale in a manner of use. The broken line showing is included for the purpose of illustrating environmental elements only and forms no part of the claimed design.
